Assistant Examiner — Calvin E Vansant

(57) **CLAIM**

The ornamental design for a sanitary towel, as shown and described.

DESCRIPTION

1.-2. Sanitary towel

1.1 : Top

1.2 : Bottom

2.1 : Top

2.2 : Bottom

Reproduction 1.1 shows the design with a rectangular base body with an hourglass-shaped absorbent pad and a transverse stripe being attached transversely at the base body and laterally overlapping said base body by forming rectangular side wings from a top view; reproduction 1.2 shows the design with a rectangular base body with an hourglass-shaped absorbent pad and a transverse stripe being attached transversely at the base body and laterally overlapping said base body by forming rectangular side wings from a bottom view; reproduction 2.1 shows the design with a rectangular base body with an hourglass-shaped absorbent pad and rectangular side wings being attached at the long sides of said base body from a top view; reproduction 2.2 shows the design with a rectangular base body with an hourglass-shaped absorbent pad and rectangular side wings being attached at the long sides of said base body from a bottom view.
